UNITED STATES PATENT OFFICE

DONALD M. SMITH, OF WESTMORELAND COUNTY, PENNSYLVANIA, ASSIGNOR TO McKEE GLASS COMPANY, OF JEANNETTE, PENNSYLVANIA, A CORPORATION OF PENNSYLVANIA

DESIGN FOR A VASE

Application filed December 16, 1929. Serial No. 33,806. Term of patent 3½ years.

To all whom it may concern:

Be it known that I, DONALD M. SMITH, a citizen of the United States of America, and residing on the Harrison City Road, in the county of Westmoreland, State of Pennsylvania, have invented a new, original, and ornamental Design for a Vase, of which the following is a specification, reference being had to the accompanying drawing, forming a part thereof, in which—

I claim:

The ornamental design for a vase, as shown.

This specification signed this 11th day of December, 1929.

DONALD M. SMITH.
